UNITED STATES PATENT OFFICE.

LANSING ONDERDONK, OF NEW YORK, N. Y., ASSIGNOR TO UNION SPECIAL SEWING MACHINE CO., OF CHICAGO, ILLINOIS, A CORPORATION OF ILLINOIS.

LOOPER-OPERATING MECHANISM FOR SEWING-MACHINES.

No. 839,075.

Specification of Letters Patent.

Patented Dec. 18, 1906.

Application filed May 21, 1901. Serial No. 61,270.

To all whom it may concern:

Be it known that I, LANSING ONDERDONK, a citizen of the United States, residing at New York, in the county of New York, State 5 of New York, have invented certain new and useful Improvements in Looper-Operating Mechanism for Sewing-Machines, of which the following is a description, reference being had to the accompanying drawings, and to 10 the letters of reference marked thereon.

My invention relates to an improvement in sewing-machines, and particularly to a looper-operating mechanism therefor, the object being primarily to provide a looper 15 mechanism for post and post-cylinder machines of the type illustrated in my application for Letters Patent filed of even date herewith, Serial No. 61,272.

The invention consists in the various matters hereinafter described, and referred to in the appended claims.

In the accompanying drawings, which illustrate the invention, Figure 1 is a plan view of one form of a sewing-machine embodying my invention. Fig. 2 is a side elevation, the bed-plate being in longitudinal vertical section. Fig. 3 is a transverse vertical section on line 4-4 of Fig. 2, the cover of the vertical post being removed. Fig. 4 is a detail showing the eccentrics and the wrist-pin, the latter for operating the looper-lever. Fig. 4^a is a face view of the larger eccentric. Fig. 5 is a detail perspective illustrating the feed and looper operating devices, the space separating the two mechanisms being exaggerated.

Briefly, it comprises a hollow horizontal angular casing A, from the rear end of the member A' of which rises the gooseneck, which is at right angles to the said case member A', and parallel with the forward case member A² rises the hollow post A³, from the upper end of which projects the rearwardly-extending cylindrical bed-plate or horn A⁴, parallel with the case member, but in a higher plane. The upper tension mechanism, the needle-bar N, its needle-clamp u and needle-lever N', presser-foot P, and presser-bar P' are all of the usual construction and need not be herein described.

C is the horizontal drive-shaft, provided with two cranks c e, to which are connected the rear ends of connecting-rods C' C', connected at their opposite ends to cranks d d in

the line shaft D. The left-hand end of the line or drive shaft D has within its post A³ 55 two eccentrics d² d³, the former carrying a wrist-pin d⁴.

F represents the feed-dog-carrying bar, the feed-dog being shown at F', herein illustrated as feeding the work off the end of the cylinder or in a direction away from the operator and pivotally connected at its end nearest the operator to the upper forked end f² of main feed-lever F², the lower end of said lever being strapped to the larger eccentric d² on shaft D. The lever F² is further acted upon by the auxiliary lever F³, forked at its lower end f⁴ to straddle the smaller eccentric d³ of shaft D. This lever is pivoted at its upper end to the right side of lever F² 70 by a pivot-screw f⁵ and has a sliding adjustable pivot connection with the post A³. By this arrangement the four motions are imparted to the feed-dog.

L is the looper-shaft, mounted to slide and 75 rock in bearing-blocks below the feed-bar F and provided at its end farthest from the operator with two loopers l l, which coact in the usual manner with the two needles to form parallel rows of stitches. The near or front end of the looper-shaft passes through the yoke f² of lever F² and is there provided with a transverse operating-arm comprising a clamp l', provided with a ball l², engaged by a socket l³ on the upper end of the looper-operating lever L', the lower end of said lever having a socket l⁴, receiving the ball d⁴, carried by the eccentric d².

In order that the looper-shaft may have longitudinal or needle-avoiding movement in addition to the rocking or loop taking and loop leaving movement, I provide a transverse vertically-rocking tubular bearing L², pivoted at l⁵ to a bracket a⁶ on the inside of the post A³, and in this bearing slides the shank l⁶ of the ball l', engaged by the socket l⁸ on the lever L' just below socket l³. It will be seen that as the lower end of the lever L' is carried around by the wrist-pin d⁴ its upper end will rock the looper-shaft and also oscillate on the ball l', and so reciprocate the looper-shaft. One-half of each of the sockets l⁷ l⁸ is formed in the removable cap l⁹, secured in place by the screw l¹⁰. To vary the position of the wrist-pin d⁴, it is mounted 105 on a ring d⁹, let in an annular recess d¹⁰,

formed in the face of the eccentric d^2 and provided with a series of slots or openings d^11 , through certain of which pass the two attaching-screws d^{12} .

5 Having thus described my invention, what I claim as new, and desire to secure by Letters Patent, is—

1. A looper-operating mechanism for sewing-machines, comprising a horizontal shaft, 10 and means for operating it, a looper-support, a looper thereon, means for imparting to said looper-support a movement about its axis, and a movement transverse thereto, said means including a vertically-arranged 15 looper-operating lever connected at its lower end to the shaft, and at its upper end connected to the looper-support and having also a sliding pivot connection with a stationary part of the machine-frame; substantially as 20 described.

2. A sewing-machine comprising a framework or casing having a horizontal and a vertical member, and a shaft journaled in the horizontal member, suitable feeding mechanism, 25 a looper-support with means for vibrating it backward and forward and sidewise, said means including a looper-operating lever connected at its lower end to said horizontal shaft and at its upper end freely connected 30 to the looper-support and having also a pivotal connection with the vertical member; substantially as described.

3. A sewing-machine comprising a framework or casing having a horizontal and a vertical member, and a shaft journaled in the horizontal member, suitable feeding mechanism, 35 a looper-support with means for vibrating it backward and forward and sidewise, said means including a looper-operating lever connected at its lower end to said horizontal shaft and at its upper end freely connected 40 to the looper-support and having also a sliding pivotal connection with the vertical member; substantially as described.

45 4. A sewing-machine, comprising a casing or framework, having a horizontal and a vertical member, and a shaft journaled in the horizontal member, a feeding mechanism, a rocking and sliding looper-shaft at the upper 50 end of the vertical member, and a looper-operating lever connected at its lower end to said shaft, and at its upper end pivotally-connected to the looper-supporting shaft, and having a pivotal and sliding connection below the looper-shaft with said vertical frame member; substantially as described.

5. A sewing-machine, comprising a casing or framework, having a horizontal and a vertical member, and a shaft journaled in the 60 horizontal member, and provided at the base of the vertical member with a wrist-pin, a feeding mechanism, a rocking and sliding looper-shaft at the upper end of the vertical base member, and a looper-operating lever,

connected at its lower end to the said wrist-pin, pivotally connected at its upper end to the said looper-shaft, and having a pivotal and sliding connection below the looper-shaft, with said vertical frame member; substantially as described. 65

6. A looper-operating mechanism for sewing-machines, comprising a looper-support, means for sliding and rocking the same including an operating-shaft, a vertically-arranged lever connecting the shaft with the 75 looper-support, said lever being pivotally connected with the looper-support, a rocking bearing fixed to the machine-frame, and a yielding pivot connection between the lever and the rocking bearing; substantially as de- 80

7. A looper-operating mechanism for sewing-machines, including a looper-support and a lever having pivotal connection with the looper-support, a sliding pivot on which 85 said lever swings, and a rocking bearing transverse to the feed in which the sliding pivot is supported, said rocking bearing being supported on a fixed part of the machine-frame; substantially as described. 90

8. A looper-operating mechanism for sewing-machines, comprising a sliding and rocking looper-support, an operating-lever pivoted thereto at one end, a driving-shaft connected with the opposite end of said lever, a 95 rocking bearing pivoted to a stationary part of the machine, a sliding pin supported in the rocking bearing, said sliding pin having a pivotal connection at its outer end with the operating-lever; substantially as described. 100

9. A looper-operating mechanism for sewing-machines, comprising a longitudinally and laterally vibrating looper-support, an operating-lever pivoted thereto, means for operating said lever, a block pivoted to a stationary part of the machine, a pin or shaft 105 sliding in said block, and pivoted to the operating-lever; substantially as described.

10. In a sewing-machine, having a vertical post or casing member, a looper mechanism 110 therefor including a vertically-arranged operating-lever, a transversely-arranged sliding and rocking support for the looper, a direct pivotal connection between the upper end of the looper-operating lever, and the looper-support, a rocking bearing attached to the post, a pin arranged transversely of said rocking bearing and having sliding movement therein, and pivotally connected at its outer end with the looper-operating lever below its 115 point of pivotal connection with the looper-support; substantially as described. 120

In testimony whereof I affix my signature in presence of two witnesses.
